UNITED STATES PATENT OFFICE.

ALPHONSE LANGLOIS, OF RUTLAND, VERMONT.

DESIGN FOR A LAMP-STAND.

SPECIFICATION forming part of Design No. 34,572, dated May 28, 1901.

Application filed May 1, 1901. Serial No. 68,399. Term of patent 7 years.

To all whom it may concern:

Be it known that I, ALPHONSE LANGLOIS, a citizen of the United States, residing at Rutland, in the county of Rutland, State of Vermont, have invented and produced a certain new and original Design for a Lamp-Stand, of which the following is a specification, reference being had therein to the accompanying drawings.

10 Figure 1 is a perspective of my invention. Fig. 2 is a vertical section thereof, and Fig. 3 is a plan.

As shown in the drawings, the leading or material feature of this design consists of the 15 rectangular base A, having the vertical standard B, supporting at its upper end an annular plate C. The base A is composed of members A', connected by parallel straight bars A², spaced apart, while the bars A' extend 20 above and below the bars A² and the bars A⁴ above the bars A² to form flanges. The standard B is circular in cross-section and the plate

C, carried at the upper end thereof, is provided with a depending flange C', extending about the circular aperture in the plate, while 25 at the rear of this aperture and at the top of the standard the outer walls of the plate extend backward parallel with each other, as shown at C². At the point of connection with the base of the standard B one of the bars A' 30 is provided with a curved projection A³, while the plate C at the upper end of the standard is provided with a similar projection C³.

Having described my invention, what I claim as new, and desire to secure by Letters 35 Patent, is—

The design for a lamp-stand as hereinbefore shown and described.

In testimony whereof I affix my signature in presence of two witnesses.

ALPHONSE LANGLOIS.
